UNITED STATES PATENT OFFICE.

ROLAND MARSLAND, OF ESSINGTON, PENNSYLVANIA, ASSIGNOR TO WESTINGHOUSE ELECTRIC & MANUFACTURING COMPANY, A CORPORATION OF PENNSYLVANIA.

GOVERNOR.

Application filed February 20, 1924. Serial No. 694,141.

To all whom it may concern:

Be it known that I, ROLAND MARSLAND, a citizen of the United States, and a resident of Essington, in the county of Delaware and State of Pennsylvania, have invented a new and useful Improvement in Governors, of which the following is a specification.

My invention relates to governing apparatus of the character shown, described and claimed in the application of Alexander T. Kasley, Serial No. 610,514, filed January 3, 1923, and assigned to the Westinghouse Electric and Manufacturing Company, and it has for an object to provide apparatus of this character which shall be simplified from the standpoint of construction and manufacture.

A further object of my invention is to provide centrifugal fluid pressure relief means for apparatus of the character referred to which shall be carried by the shaft of the machine governed.

Apparatus made in accordance with my invention is illustrated in the accompanying drawings forming a part of this application, in which Fig. 1 is a view, partly in section, of a portion of a turbine showing my improved governing apparatus applied thereto; Fig. 2 is a sectional view upon an enlarged scale of the governing apparatus; Fig. 3 is a sectional view on a still larger scale of the fluid motor employed with the apparatus, and Fig. 4 is a sectional view of the speed responsive valve employed there-with.

Referring now to the drawings for a better understanding of my invention, I show a turbine or equivalent apparatus 10 having a shaft 11 and an admission valve 12. Opening and closing of the admission valve to increase or restrict the supply of steam or motive fluid to the turbine is under the control of my improved speed-responsive fluid governing apparatus.

The speed-responsive fluid governing apparatus comprises a motor device, at 13, which is provided with an actuated stem 14, connected to a lever 15, fulcrumed at 16, the lever being connected to the stem 17 of the admission valve 12. The motor device, at 13, comprises a movable abutment or piston 18 which is movable in one direction by fluid admitted to the chamber or cylinder 19. The piston 18 and the stem 14 are moved

in the other direction by means of a compression spring 20.

Motive fluid is supplied to and exhausted from the cylinder 19 above the piston 18 by means of a port 22 (better illustrated in Fig. 3) in the head 23 of the cylinder 19, the port 22 being adapted to be placed in communication with the annular fluid pressure supply channel 24 or with the exhaust chamber or passage 25, also arranged in said head 23. To this end, the head 23 is provided with a cylinder 26 which communicates with the supply channel 24, the supply and exhaust port 22, and the exhaust chamber or passage 25. A piston valve 27 is arranged within the cylinder 26 and it has a piston portion 28, which is approximately of the same width as the annular passage 29 which communicates with the supply and exhaust passages 22 leading to the cylinder 19. The piston valve 27 is provided with portions 30 and 31 of less diameter than the cylinder 26 and arranged respectively above and below the piston valve portion 28.

If the piston valve member 27 is moved slightly upwardly the annular supply channel 24 will be placed in communication with the annular channel 29, communicating with the supply and exhaust ports or passages 22 by means of the portion 31 of lesser diameter than the piston valve 27, with the result that fluid under pressure supplied from the impeller 32 to the passage 33 and in turn to the passage 34 in the head 23 which communicates with the annular passage 24, as shown by the dotted lines, passes around the depressed portion 31, enters the annular passage or chamber 29, and thence passes through the ports or passages 22 into the cylinder 19 with the result that the piston 18 is moved downwardly against the force of the spring 20. Downward movement of the piston valve 27 results in placing the cylinder 19 in communication with the exhaust passages 25 by way of the passages 22, the annular chamber 29, and the depressed portion 30.

The piston valve is moved upwardly and downwardly in the manner referred to by means of fluid pressure in one direction and by means of the spring 20 in the other direction. To this end, the piston valve 27 has an operating piston 36 connected there-

to and arranged within a cylinder 37. A stem 38 extends above the piston 36 and through a suitable opening in the cover plate 39 of the casting containing the cylinder 19. The stem 14 connected to the piston 18 extends through and slides freely with respect to the piston valve 27, the piston 36 and the stem 38. An abutment 40 is carried at the upper end of the stem 38 and a spring abutment 41 surrounds the stem 14 and rests against the abutment 40. An abutment 42 is arranged about the stem 14 at the other end of the spring and it is adjustable with respect to the stem in order that a desired degree of pressure may be placed upon the spring 20. From the structure described, it will be apparent that the spring 20 normally exerts its force in such a way as to tend to move the piston 36 downwardly and the piston 18 upwardly. In other words, the pistons 18 and 36 are normally biased toward each other.

The normal position for the operating piston 36 is that in which the forces above the piston are balanced by the fluid pressure force below such piston, at which time the piston valve 27 occupies a neutral or cut-off position, or a position in which the piston portion 28 covers the annular chamber 29 communicating with the passages 22. If pressure is relieved beneath the piston 36, the latter will move downwardly under the influence of the force of the spring 20 and of such fluid pressure as may have accumulated above the piston 36. On the other hand, with the building up of pressure beneath the piston 36, the spring 20 is overcome and the piston valve moved upwardly. Downward and upward movement of the piston 27 results in exhausting and supplying motive fluid to the cylinder 19 in the manner already referred to. The means whereby fluid pressure may be built up and relieved beneath the piston 36 will now be described.

It will be seen that the piston valve 27 surrounds the rod 14 with slight clearance so as to form a throttling passage 43 which communicates at its lower end with ports 44 leading to the annular channel 24 and with ports 45 leading to the cylinder 37 beneath the piston 36. The throttling passage or orifice connection 43 tends to retard the building up of pressure of fluid beneath the piston 36, such fluid being supplied from the impeller 32, through the passage 33, the chamber 34, the annular channel 24, the ports 44, the orifice connection 43 and the ports 45. The lower end of the cylinder 37 communicates with a passage 46 leading to a passage 47 which communicates with an annular channel 49 arranged in a bearing 50 for the shaft 11. The shaft 11 is provided with passages 51 arranged as closely as possible to the circumferential

bearing portion thereof. Each of the latter passages communicates with the annular channel 49 at one end and with the interior of the speed-responsive relief valve means, at 52.

The speed-responsive valve means, at 52, Fig. 4, comprises a casing 53 which is secured to a flange 55 carried by the shaft 11. The casing 53 in effect constitutes an enlarged portion of the shaft 11 which is provided with thrust collars 56 and 57 and which is connected to the impeller 32. As shown, the casing 53 is provided interiorly with a diametral shell 58 which fits in diametrically opposed openings 59 and 60 in the casing or head 53. The shell 58 is secured in position with respect to the casing 53 by any suitable means known to the art. The shell 58 is provided with valve ports 62 near one end, which cooperate with an interior cylindrical valve member 63, which is provided with a depressed portion 64 at its upper end to provide a cut-off shoulder 65. Normally, the cylindrical piston valve member 63 occupies such a position that the shoulder 65 cooperates with the outer edge or end 66 of the cylinder 58 to limit escape of fluid through the ports 62 and the depressed portion 64 and then out between the edges 65 and 66.

The mass of the piston valve member 63 is so distributed that its center of gravity is located nearer to the valve end than the shaft axis is. With this arrangement, upon the attainment of a predetermined speed, centrifugal force is effective to move the piston valve member 63 outwardly in order that the pressure of fluid beneath the piston 36 may be relieved.

The piston valve member 63 of the valve construction at 52 is moved inwardly under the influence of a spring 67 which rests at one end against an abutment 68 connected to the shell or cylinder 58 by means of a central bolt 69 and an abutment 70 cooperates with the other end of the spring 67 and it has a spherical fitting 71 with respect to a supporting member 72 which fits against a shoulder 73 carried by the interior of the shell or casing 58. The abutment 68 is provided with suitable openings 74 with respect to the opening 60 in order that the relief of fluid may be readily permitted. The valve member 63 is provided with an extension 75 which cooperates with the head 115 of the casing or cylinder 58 in order to limit movement of the piston valve member 63 to an extent sufficient to provide for cut-off between edges 65 and 66. The abutment 68 has screw threaded connections with respect to the bolt 69 so that the tension of the spring 67 may be varied, thereby regulating the speed at which the piston valve member 63 is forced outwardly to relieve pressure of fluid beneath the piston 36 in the manner 120

already referred to. Screw means 76 is preferably carried by the head 53 in order to prevent loosening of the abutment 68.

From Fig. 4, it will be seen that the piston valve member 63 defines small clearance with respect to the cylinder 58 except for a short portion 64' immediately below the depressed portion 64. The cylinder 58 is provided with a plurality of ports 77 which communicate with the clearance space 78 between the piston valve 63 and the cylinder 58 and with the space 79 between the head of the cylinder 58 and the head of the piston valve 63. This construction allows for a piston valve which requires very slight pressure as it has only limited engagement with respect to the cylinder 58. Owing to the self-centering spherical connection dimensions constituted by the abutment 70 and the supporting member 71, the piston valve member 63 is maintained centered with respect to the bolt 69 so that it may have the requisite inward and outward movement or order to cut off or open up the exhaust.

As already referred to, the equilibrium position of the piston 36 and the cut-off position of the piston valve 27 are determined by a condition of equilibrium of forces effective above and below the piston 36. The pressure of fluid accumulating above the piston 36 may be varied by an appropriate pressure relief device which is adapted to cooperate with a passage 80 leading to the cylinder 37 above the piston 36 and which communicates with a chamber 81. A valve 82 is adapted to close the passage 80 and it is normally maintained in closed position by means of a spring 83 arranged between an abutment 84 carried by the valve and an adjustable abutment 85 carried by a stem 86 which has a threaded connection with respect to a supporting standard 87. The chamber 81 also communicates with a passage 88 which leads to a drain passage 89 communicating with the bearing or oil supply space or chamber 90 by means of a port 91. Oil passing the valve 82 and which is exhausted from the cylinder 19 through the passage 25 flows to the chamber 90 and from thence to the bearings 56 and 57.

The impeller 32 is arranged within a suitable chamber 92 and the latter is supplied with oil not only from the bearings 56 and 57 but from the oil reservoir 93 which communicates with drains 94 and 95 for the bearing 50, for the centrifugal relief valve means 52 and for the bearings.

From the apparatus described, the operation thereof will be apparent.

The impeller 32 develops pressure of oil which varies substantially as the speed of the shaft 11. This oil under pressure is in constant communication with the space be-

neath the piston 36 by way of the passage 34, the port 44, the orifice connection 43, and the ports 45, the purpose of the orifice connection being to allow for a sudden relief of pressure beneath the piston 36 by the speed responsive valve, at 52. When the piston 36 is in equilibrium, the piston valve 27 occupies a neutral or cut-off position, whereby the piston 18 is held blocked in the cylinder 19 by the fluid which is cut off therein by the piston valve portion 28. This equilibrium position of the piston 36 is determined by the balancing of forces above and below it. The forces effective above are those due to the spring 20 and to the pressure of fluid which may pass by the piston 36 and accumulate thereabove in the cylinder 37, the adjustment of the escape valve 82 permitting of a variation in the pressure of this accumulating fluid. Pressure below the piston 36 is dependent wholly upon the position of the valve member 63. If the latter is slightly open, permitting of the escape of oil, pressure beneath the piston 36 declines with the result that the latter moves downwardly under the influence of the spring 20; however, such downward movement of the piston 36 results in downward movement of the piston valve 27 so that the piston valve portion places the ports 22 and the annular chamber 29 in communication with the exhaust chamber 25, with the result that the tension of the spring 20 is effective to move the piston 18 upwardly. From this, it will be seen, that the tension of the spring 20 is lowered by the upward movement of the piston 18 and the stem 14, this upward movement continuing until the pressure of the spring 20 above the piston 36 is sufficiently relieved so that the force of the fluid pressure beneath the piston 36 comes into a condition of substantially equilibrium with respect to the force of the spring and of the fluid pressure above the piston, whereupon, the piston 36 is moved upwardly until the piston valve occupies a neutral or cut-off position. Upon a decrease in speed of the motor or turbine shaft 11 the valve member 63 moves inwardly to entirely restrict the escape of fluid whereupon, pressure accumulates beneath the piston 36 and it is effective to move the latter upwardly in order to place the pressure supply channel 24 and passage 34 in communication with the annular channel 29 and passage 22 in order to supply fluid to the cylinder 19 to move the piston 18 downwardly.

The initial upward movement of the piston 36 results in a slight increase in tension on the spring 20. Downward movement of the piston 18 results in further increase in tension on the spring 20, this downward movement of the piston 18 continuing until the compressing force of the spring 20, together with the fluid pressure above the

piston 36 is in equilibrium with the increased fluid pressure beneath the piston 36, whereupon, the latter piston moves back so as to move the piston valve 27 to a neutral or cut-off position.

The effect of adjusting the escape valve 82 is to regulate the back pressure acting above the piston 36. To increase the back pressure calls for a corresponding greater oil pressure below the piston 36 in order that an equilibrium condition may be attained. On the other hand, a decrease in the back pressure results in a lower oil pressure below the piston 36 in order to attain an equilibrium condition. Hence, with this relief valve, the normal running speed of the turbine may be changed. Lowering the back pressure means corresponding lower pressure below the piston 36 and the latter condition means a greater opening condition of the speed-responsive valve, at 52, which corresponds to a higher speed of the turbine. On the other hand, raising of the back pressure above the piston 36, means that pressure beneath that piston must be correspondingly raised in order that an equilibrium condition may be attained. Hence, the speed of the turbine must be lowered in order that the speed-responsive valve, at 52, may be sufficiently restricted in order to allow for this accumulation of pressure.

From the foregoing, it will be apparent that, whenever the piston 36 moves in either direction, the piston 18 moves in an opposite direction, so that the tension on the spring 20 may be sufficiently changed in order that the forces effective on the piston 36 may attain an equilibrium condition making it possible to bring the piston valve back to a neutral or cut-off position. Any

oil which passes the escape valve 82 or which escapes from the discharge passage or chamber 35 enters the chamber 90 which communicates with the bearings 56 and 57 to supply oil thereto.

45

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claim.

55

What I claim is:

The combination with a turbine having an admission valve and a rotor shaft, a lever connected to the admission valve, a spring tending to move the lever in one direction to close the admission valve, a stem carried by the lever, a piston carried by the lower end of the stem, a cylinder for the piston, means driven by the shaft for developing fluid under pressure, a valve for controlling the admission and exhaust under pressure to one side of said piston, a piston carried by said valve and having its upper end bearing against said spring, means for normally applying pressure of fluid developed by said pressure-developing means to the face of said piston connected to the valve and which is opposite to the spring and centrifugal means carried by the shaft for relieving pressure of fluid applied to said piston.

65

In testimony whereof, I have hereunto subscribed my name this 18th day of February 1924.

75

ROLAND MARSLAND.

piston 36 is in equilibrium with the increased fluid pressure beneath the piston 36, whereupon, the latter piston moves back so as to move the piston valve 27 to a neutral or cut-off position.

The effect of adjusting the escape valve 82 is to regulate the back pressure acting above the piston 36. To increase the back pressure calls for a corresponding greater oil pressure below the piston 36 in order that an equilibrium condition may be attained. On the other hand, a decrease in the back pressure results in a lower oil pressure below the piston 36 in order to attain an equilibrium condition. Hence, with this relief valve, the normal running speed of the turbine may be changed. Lowering the back pressure means corresponding lower pressure below the piston 36 and the latter condition means a greater opening condition of the speed-responsive valve, at 52, which corresponds to a higher speed of the turbine. On the other hand, raising of the back pressure above the piston 36, means that pressure beneath that piston must be correspondingly raised in order that an equilibrium condition may be attained. Hence, the speed of the turbine must be lowered in order that the speed-responsive valve, at 52, may be sufficiently restricted in order to allow for this accumulation of pressure.

From the foregoing, it will be apparent that, whenever the piston 36 moves in either direction, the piston 18 moves in an opposite direction, so that the tension on the spring 20 may be sufficiently changed in order that the forces effective on the piston 36 may attain an equilibrium condition making it possible to bring the piston valve back to a neutral or cut-off position. Any

oil which passes the escape valve 82 or which escapes from the discharge passage or chamber 35 enters the chamber 90 which communicates with the bearings 56 and 57 to supply oil thereto.

45

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claim.

55

What I claim is:

The combination with a turbine having an admission valve and a rotor shaft, a lever connected to the admission valve, a spring tending to move the lever in one direction to close the admission valve, a stem carried by the lever, a piston carried by the lower end of the stem, a cylinder for the piston, means driven by the shaft for developing fluid under pressure, a valve for controlling the admission and exhaust under pressure to one side of said piston, a piston carried by said valve and having its upper end bearing against said spring, means for normally applying pressure of fluid developed by said pressure-developing means to the face of said piston connected to the valve and which is opposite to the spring and centrifugal means carried by the shaft for relieving pressure of fluid applied to said piston.
